UNITED STATES PATENT OFFICE.

SILAS A. PARKER, OF MORRISTOWN, NEW JERSEY, ASSIGNOR TO THEODORE R. PETERSON, OF PROVIDENCE, RHODE ISLAND.

NON-REFILLABLE BOTTLE.

1,194,415.

Specification of Letters Patent. Patented Aug. 15, 1916.

Application filed June 30, 1914. Serial No. 848,185.

To all whom it may concern:

Be it known that I, SILAS A. PARKER, a citizen of the United States, and a resident of Morristown, county of Morris, and State 5 of New Jersey, have invented certain new and useful Improvements in Non-Refillable Bottles, of which the following is a specification.

This invention relates to an improved bottle 10 that is constructed so that it is not adapted for re-filling, being formed with a neck having means inside of it for preventing the entrance of liquid into the bottle.

The bottle is designed to be one that saves 15 expense in manufacture and in which the manufacture and assembling of the parts are easy.

The invention is further designed to provide a bottle in which the closure, usually a ball, is positively seated when the bottle is substantially upright and in which the closure is free to leave its seat when the bottle 20 is turned to a "pouring" position.

The improved bottle is one in which the 25 valve or closure is not entirely opened when the bottle is held upright and then jerked up and down, which prevents the entry of liquid from the neck. This is a new feature, as it is possible in previous bottles to pour 30 liquid into the neck, the neck becoming full above the valve. Then when the bottle is jerked up and down as in shaking, the intermittent opening of the valve will permit the entrance of liquid under the valve. This is 35 prevented in the present improved form of bottle.

Another object of the invention is to provide a thimble which serves to force the valve shut, which acts to prevent entry of liquid to the valve unless the thimble is raised, and it also acts as a cup or holder 40 into which the liquid passes from the bottle and it then overflows which distributes the flow around the inside of the neck. This 45 thimble or cup also acts to return the liquid between the valve and outlet, to the bottle, when the bottle is turned up when the pouring is finished.

The invention is illustrated in the accompanying drawing, in which—

Figure 1 is a vertical view of the top part of a bottle, showing it in section. Fig. 2 is a similar view of the bottle turned up side down to illustrate the parts in the position

they occupy when liquid is being poured 55 from the bottle. Fig. 3 is a section on line 3—3 in Fig. 1, and Fig. 4 is a top view of the bottle neck.

The bottle neck is preferably made of two parts, this being done in order to make the 60 manufacture of the separate parts easy, and also to make it easy to assemble the parts of the bottle.

The bottle 10 is of any form, and it has a neck portion which is made of a lower part 65 11 having a passage 12 therein, the passage 12 extending up through a nozzle 13 which projects above the shoulder 14 to a considerable extent. The upper portion 15 of the bottle neck is of material length and has a 70 screw-threaded portion that fits on a screw-threaded portion of the lower bottle neck part 11 so as to make a screw-threaded joint 16, although it will be evident that other forms of fastening the parts together can be 75 employed. The parts are permanently fastened by coating the screw-threaded parts with proper adhesive, which joints them together when it dries, and the part 15 is permanently attached to the lower bottle neck 80 portion 11.

The nozzle 13 is provided with an outlet 90 on which a suitable closure is adapted to be seated to close the nozzle to prevent evaporation of the contents of the bottle and also to 85 prevent the entrance of liquid from the bottle neck into the bottle. The preferred form of valve or closure is a ball 17 which fits into a recess or countersunk part 18 at the outlet end of the nozzle. When the bottle is upright, as in Fig. 1, the ball rests on the outlet 95 of the nozzle. The thimble or cup 19 fits in the bottle neck and has a top portion 20 and an apron or depending portion 21, this being formed by reason of a recess 22 which extends up from the bottom of the thimble 19, this recess being of considerable length so that the ball can move relative to the thimble when the thimble is removed from the nozzle.

To permit the passage of liquid around 100 the thimble suitable channels can be provided, one method being shown in the drawing, in which the thimble has passages or indentations 23 in its periphery to permit the passage of liquid between the outside of 105 the thimble and the inside of the bottle neck. When the bottle is in the position shown in Fig. 1 the cup or thimble 19 rests

on the ball 17 and holds it in place. The ball is usually made of metal, and while it probably will seat itself, the thimble, by reason of the round end 24 of its recess, insures the centering of the ball, since the recess 24 and the recess 18 both act to move the ball to its seated position and to hold it there.

When the bottle is turned over so as to pour liquid from it the thimble and the ball both move. The thimble slides in the bottle neck to the position shown in Fig. 2, being limited in its movement by a suitable stop 25 which, in the form shown, consists of a plate having recesses or perforations 26 therein to permit the passage of liquid. Other forms of spiders or perforated stops besides the exact form shown can be employed in my improved bottle.

When the bottle is in the position shown in Fig. 2 the liquid flows out through the passage 12 and into the recess 22 of the thimble 19 and flows over the edges of the thimble and then down through the passages provided for its flowing between the thimble and the bottle neck. In the form illustrated it would be, therefore, down through the passages 23. This distributes the liquid to a great extent and makes an even flow. If, for any reason, the cup or thimble should be inclined to stick, the weight of the ball would act to move the thimble to its open position. The stop 25 is so disposed that the lower end of the thimble does not project far enough beyond the end of the nozzle to permit the escape of the ball 17, the usual disposition of it being such as to hold the thimble a slight distance beyond the nozzle, as shown in Fig. 2.

When the pouring operation is completed and the bottle is again permitted to take its upright position the closing of the thimble on the nozzle has a tendency to force the liquid in the thimble back into the bottle, and an unappreciable, if any, amount of liquid will be outside of the valve of the bottle. The ball 17 is not secured to the thimble, but being loose therein it can independently seat itself on the end of the nozzle, and then when the thimble comes down it insures the seating of the ball and the closing of the nozzle, so that if the user neglects to put a cork in the bottle, which

can be done if desired, there is no evaporation of the liquid in the bottle.

The apron 21 extending down around the nozzle acts to prevent the introduction of liquid into the bottle by filling the bottle neck above the ball and then shaking the bottle, that is jerking it with an up and down motion. The possibility of filling by this method is prevented because the air space in the thimble acts to hold out liquid, and in addition thereto, the upward movement of the thimble and ball does not provide sufficient clearance for the entrance of liquid, particularly when it is borne in mind that the ball is loose from the thimble and descends more quickly and is seated on the nozzle before the thimble is back to its normal position, and in this way act to prevent the entrance of liquid into the bottle by means of a rapid up and down motion of the bottle with its neck filled with liquid.

The lower part of the bottle neck with its nozzle 13 is easily made. The upper portion 15 of the bottle neck is also easily made, and with the simple form of ball 17 and thimble 19 they are easily and cheaply made and assembled. When the bottle is filled the ball is put in place, the thimble is placed over the ball, and then the upper neck portion 15 is screwed into place, or otherwise fastened, and when permanently secured to the bottle the parts are in operative position and but little time is spent in their assembling.

Having thus described my invention I claim:

In a non-refillable bottle, a neck, a stop piece therein provided with a passage for liquid, an elongated nozzle within the bottle neck, a thimble within the bottle neck and having a sliding fit upon and guided by said nozzle, liquid passages being provided between said thimble and neck, and the bottom of the thimble and the end of the nozzle being provided with recessed seats in alinement with one another, and a ball adapted to be received in said seats.

In testimony that I claim the foregoing, I have hereunto set my hand, this 20th day of June, 1914.

SILAS A. PARKER.
